UNITED STATES PATENT OFFICE.

RICHARD WEBB BURNETT, OF MONTREAL, QUEBEC, CANADA.

DUMP-CAR DOOR.

1,017,281.

Specification of Letters Patent.

Patented Feb. 13, 1912.

Application filed January 16, 1911. Serial No. 602,976.

To all whom it may concern:

Be it known that I, RICHARD WEBB BURNETT, a citizen of the United States of America, residing at No. 42, The Linton, 5 Montreal, Dominion of Canada, Province of Quebec, have invented certain new and useful Improvements in Dump-Car Doors, of which the following is a specification.

The invention relates to dump cars and 10 particularly to means for closing and sealing the doors of dump cars.

The object of the invention is to provide a door that will not leak, at its closing edge and in which the tendency of the load will 15 be to tighten the seal.

In the construction of doors in dump cars hitherto the tendency of the load has been to open the door and cause leakage through the opening whereas with the present invention the load pressure cannot open the 20 door but tends to make a perfect closure.

Reference is made to the annexed drawings in which—

Figure 1, is a perspective view of a portion 25 of the hopper bottom of a dump car. Fig. 2, is a sectional view of a locking mechanism adapted to a flush bottom dump car.

In the form shown in Fig. 1, C, is part 30 of the center sill of the car supporting the hopper wall B. To this hopper wall B, is suitably hinged a door A, by means of a hinge A². In the form shown in Fig. 2, the door A, is hinged directly to the floor of the car C², and provides a flush bottom to the 35 car when closed. The outer edge of the door A, has an edge portion A¹, of sufficient width to match the lower flange of the sill D, of the car when the door is closed. Secured to the sill D, is the plate F, to which 40 by means of a continuous hinge is hinged the angle plate E. This plate E, when closed fits close to the sill D, and its lower portion E¹, supports the edge A¹, of the door A.

Suitable means of locking the angle plate E, 45 when thus closed are provided. Such a means of locking the angle plate E, is shown in Fig. 2, where the bent lever G, is pivoted to the bottom of the door A, by the hinge G¹. The lever when locked bears 50 against the outside face of the angle plate E, and thereby securely seals the edge A¹, of the door A. A bolt or catch G², holds the lever in its locked position. Other forms of

locking mechanism may be substituted for the bent lever G, without affecting the mode 55 of operation of this invention. From this construction it will appear that the load on the door A, will tend to press the edge A¹, on the part E¹, of the angle plate E, and make the contact closer. 60

Having now described the invention and its mode of operation, what I claim and desire to secure by Letters Patent is:

1. In a dump car door an edge adapted to meet the bottom of the sill of a car, and 65 an angle plate hinged to the sill and adapted to close under the door edge as described.

2. In a dump car door, an edge resting against the lower side of a sill, a plate secured to the said sill, an angle plate hinged to 70 such plate, and adapted when closed to support the door edge as described.

3. In a dump car door, the combination of a door hinged to a hopper wall, an edge adapted to meet the lower side of a sill, a 75 sill, an angle plate hinged to the said sill and adapted when closed to support the edge of the door, and means to lock the angle plate when closed as described.

4. In a dump car door the combination of 80 a door having an edge, a sill, an angle plate hinged to the said sill and means to lock the angle plate when its lower portion supports the door edge as described.

5. In a dump car door the combination 85 of a door hinged to a hopper wall, an edge to the door, a sill, a plate secured to said sill, an angle plate hinged to the plate, a bent lever hinged to the lower side of the door and means to lock the end of the bent 90 lever to the car wall as described.

6. In a dump car door, the combination 95 of a door hinged to a hopper wall, said door having an edge as wide as the door, a sill, said edge adapted to meet the lower side of the sill, an angle plate hinged to the said sill and extending across the width of the door and adapted when closed to support the edge of the door, and means to lock the angle plate when closed. 100

Signed at Montreal, this third day of December 1910 in the presence of two witnesses.

RICHARD WEBB BURNETT.
